DISPLAYER FOR PAPERBACK BOOKS

Harold L. Hudson, Gregory G. Mt. Pleasant, and Robert K. Scherzer, Liverpool, N.Y., assignors to Gaylord Bros., Inc., Syracuse, N.Y.

Filed Feb. 20, 1973, Ser. No. 333,550

Term of patent 14 years

Int. Cl. D6—04

U.S. Cl. D6—23

FIG. 1 is a perspective view of a display for paperback books showing our new design;

FIG. 2 is a side elevational view on an enlarged scale of the display with the tower rotated to be parallel to the edges of the base;

FIG. 3 is a top plan view thereof;

FIG. 4 is a bottom plan view; and

FIG. 5 is a sectional view of the tower taken on line 5—5 of FIG. 2.

We claim:

The ornamental design for a display for paperback books, substantially as shown and described.
